ART OF REFINING HYDROCARBONS

Eugene C. Herthel, Chicago, Ill., assignor to Sinclair Refining Company, New York, N. Y., a corporation of Maine

Application November 1, 1929. Serial No. 403,987

1 Claim. (Cl. 196—110)

This invention relates to improvements in apparatus for cracking hydrocarbon oils in the manufacture of gasoline, for example, in which higher boiling oil is heated to a cracking temperature in a battery of heating tubes connected in parallel arranged in a fire-heated furnace. The invention is useful, for example, in connection with the operation of cracking apparatus such as that described in Letters Patent No. 1,285,200, issued November 19, 1918, on the application of Edward W. Isom, No. 1,634,666, issued July 5, 1927, on the application of Harry L. Pelzer and myself, and No. 1,721,780, issued July 23, 1929, on my application, to Sinclair Refining Company.

In heating furnaces of the general type described in the aforementioned Letters Patent, for example, operating difficulties due to overheating localized in some of the heating tubes of the battery are sometimes encountered. This overheating, when it occurs, is frequently confined to heating tubes near the lateral boundaries of the path of travel of the heating gases over the heating tubes. This invention relates particularly to improvements in such heating furnaces minimizing any tendency toward this type of overheating.

Various hypotheses tend to explain this type of overheating, non-uniformity of oil flow through the heating tubes, lack of homogeneity of the stream of heating gases flowing over the heating tubes particularly with respect to temperature, and radiation or reradiation from adjacent walls of the heating furnace, for example. But whatever the explanation, or explanations, of the type of overheating may be, I have found that any tendency toward this type of overheating can be inhibited by restricting the flow of oil entering each of the heating tubes at a point adjacent the inlet to each of the heating tubes.

In the improved apparatus of this invention, this restriction is accomplished by orifices arranged adjacent to the inlet ends of each of the parallel-connected heating tubes in the heating furnace.

Two forms of apparatus embodying the invention are illustrated, diagrammatically and conventionally, in the accompanying drawing, and the invention will be further described in connection therewith. In the accompanying drawing, Fig. 1 is an elevation, partly in section and with parts broken away, of a pressure cracking still, Fig. 2 is a section, on an enlarged scale, on line 2—2 of Fig. 1, and Fig. 3 is a section, similar to Fig. 2, showing a modification of the apparatus illustrated in Fig. 2.

The pressure still system illustrated comprises

a drum 11, a battery of parallel connected heating tubes 12 arranged in the heating flue 13 of a heating furnace, circulating connections 14, 15 and 16 including a circulating pump 17 and a closure means 18, a line 19 for the discharge of tar during operation, a line 20 for initially charging the still and for pumping out the still at the end of a run, a reflux tower 21 connected to the still proper by means of a vapor line 22 and a return line 23 and provided with a line 24 for the introduction of raw oil, a condenser 25 connected to the reflux tower by means of a vapor line 26 including a valve 27 for maintaining and regulating the pressure in the still, and a receiver 28 connected to the condenser by means of line 29 and provided with a line 30 for the discharge of the cracked distillate product and a line 31 for the discharge of uncondensed vapors and gases.

This pressure still system illustrated may be operated, for example, as described in Letters Patent No. 1,598,136, issued August 31, 1926, or No. 1,721,779, issued July 23, 1929, on my application, to Sinclair Refining Company.

The pump 17 may be of the type, for example, described in Letters Patent No. 1,701,198, issued February 5, 1929, on the application of Thomas de Colon Tiff, to Sinclair Refining Company. The heating furnace, including the heating flue 13 in the apparatus illustrated, may be provided with means for recirculating through the heating flue a part of the heating gases as described in Letters Patent Nos. 1,574,546, and 1,574,547, issued February 23, 1926, on the applications of John E. Bell, to Sinclair Refining Company, and with means for preheating the air supplied for combustion as described in Letters Patent No. 1,623,773, issued April 5, 1927, on the application of John E. Bell, to Sinclair Refining Company.

In the apparatus of this invention, referring particularly to Fig. 2, orifices 32 are arranged adjacent the inlet ends, the lower ends in the apparatus illustrated, of each of the heating tubes 12 arranged in the heating flue 13 severally restricting the cross-section of each of the heating tubes 12 at that point. These orifices effect a restriction, fixed severally for each of the parallel-connected heating tubes, of flow through the heating tubes and, apparently in this manner, inhibit overheating localized in heating tubes near the lateral boundaries of the heating flue in which the heating tubes are arranged, probably by introducing a more or less fixed factor decreasing the proportionate effect of variable factors affecting oil-flow through the several heating

tubes or heat absorption by the several heating tubes or oil flowing therethrough.

In apparatus such as that illustrated in Fig. 2, for example, the heating tubes 12 may be 4" 5 in diameter and the orifices 32 may be 1" in diameter.

Further regulation of the operation of the heating furnace may be effected by adjusting the size of the several orifices. The orifices near 10 the center of the path of travel of the heating gases over the heating tubes may advantageously be made smaller than those near the lateral boundaries of this path, for example.

In apparatus such as that illustrated in Fig. 3, 15 for example, the heating tubes 12 may be 4" in diameter, the orifices 33 in the heating tubes in rows I and X may be 3½" in diameter, the ori-

fices 34 in the heating tubes in rows II and IX may be 3" in diameter, and the orifices 35 in the heating tubes in rows III to VIII inclusive may be 2½" in diameter.

I claim:

In apparatus for cracking hydrocarbon oils comprising a battery of heating tubes connected in parallel arranged in a fire-heated furnace, orifices adjacent the inlet ends of each of the heating tubes forming the battery severally restricting the cross-section of each of the heating tubes at that point, said orifices being smaller near the center of the path of travel of heating gases over the heating tubes than near the lateral boundaries of said path.
